CLAIM

The ornamental design for a flip up modular digital clock for automobile control panels, as shown.

DESCRIPTION

FIG. 1 is a top and right, front perspective view of a flip-up modular digital clock in an unfolded position; FIG. 2 is a front elevational view thereof in a folded position;

FIG. 3 is a right side elevational view of FIG. 2, the left side view being a mirror image thereto;

FIG. 4 is a rear elevational view of FIG. 2;

FIG. 5 is a top plan view of FIG. 2;

FIG. 6 is a bottom plan view thereof.

FIG. 1

FIG. 2

FIG. 3

FIG. 4

FIG. 5

FIG. 6
